Patented May 5, 1903.

UNITED STATES PATENT OFFICE.

GEORGE F. EHRLE, OF MILWAUKEE, WISCONSIN.

ARTIFICIAL FOOT.

SPECIFICATION forming part of Letters Patent No. 726,889, dated May 5, 1903.

Application filed August 13, 1902. Serial No. 119,506. (No model.)

To all whom it may concern:

Be it known that I, GEORGE F. EHRLE, a citizen of the United States, and a resident of Milwaukee, in the county of Milwaukee and State of Wisconsin, have invented certain new and useful Improvements in Artificial Feet; and I do hereby declare that the following is a full, clear, and exact description thereof.

10 My invention has for its object to provide simple economical artificial feet that when in use will simulate the action of natural feet and take up the jar that renders ordinary artificial feet objectionable, said invention consisting in what is hereinafter particularly set forth with reference to the accompanying drawings and subsequently claimed.

Figure 1 of the drawings represents a central longitudinal sectional view of an improved artificial foot in accordance with my invention, and Fig. 2 a transverse section of the same indicated by line 2 2 in the first figure.

25 Referring by letter to the drawings, the artificial foot herein shown consists of a layer A of ratan interposed between other layers B C of felt or other suitable material, the foot being provided with an upper play-recess b, cord-apertures c d, pin-apertures e f g, and

ankle-joint bushing h customary in artificial 30 feet of ordinary construction. The toe portion of the ratan layer A of the foot is made thinner than the remainder in order that it may more readily yield to pressure, the thickness of said layer throughout being proportioned to the weight of the person for whom 35 said foot is designed. Ratan is a cheap, light, tough, and durable flexible material that can be readily fashioned by ordinary wood-working-tools, and it has been found admirably adapted for my purpose of a yielding 40 stiffener in an artificial foot that is partly felt or other elastic material.

Having thus described my invention, what I claim as new, and desire to secure by Letters 45 Patent, is—

An artificial foot comprising layers of elastic material and an interposed layer of ratan constituting a yielding stiffener for the foot.

In testimony that I claim the foregoing I 50 have hereunto set my hand, at Milwaukee, in the county of Milwaukee and State of Wisconsin, in the presence of two witnesses.

GEO. F. EHRLE.
